H. B. HARTMAN.

SAFETY RAZOR.

APPLICATION FILED JULY 7, 1917.

1,247,268.

Patented Nov. 20, 1917.

UNITED STATES PATENT OFFICE.

HARRY B. HARTMAN, OF SCOTTDALE, PENNSYLVANIA.

SAFETY-RAZOR.

1,247,268.

Specification of Letters Patent. Patented Nov. 20, 1917.

Application filed July 7, 1917. Serial No. 179,118.

To all whom it may concern:

Be it known that I, HARRY B. HARTMAN, a citizen of the United States of America, residing in Scottdale, in the county of Westmoreland and State of Pennsylvania, have invented certain new and useful Improvements in Safety-Razors, of which the following is a true and exact description, reference being had to the accompanying drawings, which form a part thereof.

My present invention relates to safety razors and particularly to safety razors of the type in which a blade is detachably secured in a holder or clamping device to which an operating handle is attached. One main object of my invention is to provide a razor, of the type referred to, with improved means for so connecting the handle to the blade holder that the handle may be readily adjusted relative to the blade holder to vary the relation between the active cutting edge of the blade and the hand of the user, and thereby permit the razor to be held in any of the various ways in which different persons may need or prefer to hold the razor to get the best results.

A further object of the invention is to provide an improved form of blade holder adapted to provide a yielding resistance to the clamping nut of my improved handle construction without requiring the flexure of the blade for this purpose.

The various features of novelty which characterize my invention are pointed out with particularity in the claims annexed hereto and forming a part of this specification. For a better understanding of the invention, however, and the advantages possessed by it, reference should be had to the accompanying drawings and descriptive matter, in which I have illustrated and described preferred embodiments of my invention.

Of the drawings:

Figure 1 is a plan view of a complete razor.

Fig. 2 is a section taken on the line 2—2 of Fig. 1.

Fig. 3 is a section taken on the line 3—3 of Fig. 1.

Fig. 4 is a perspective view of the handle connecting means employed in Figs. 1, 2 and 3.

Fig. 5 is a section on the line 5—5 of Fig. 2.

Fig. 6 is a section taken similarly to Fig. 2, illustrating a modified form of handle connection.

Fig. 7 is a view similar to Fig. 4 illustrating the construction employed in Fig. 6. 60

Fig. 8 is a plan view of the blade holder of an existing type of razor to which my improved handle adjustment may be applied, with parts in section on the line 8—8' of Fig. 9. 65

Fig. 9 is a transverse section of the blade holder shown in Fig. 8 with my handle adjustment applied thereto.

In the drawings, and referring first to the construction shown in Figs. 1 to 5, inclusive, A represents the double-edged blade which may be either flexible or rigid and is shown as provided with central notches A' in its ends. The blade A is received in a blade holder comprising a front plate B and a back plate or guard member C. The front plate comprises a body portion on top of which the blade A rests and uprising end portions B', to which are hinged resilient lever arms B², which normally have their free ends opposite one another adjacent the center of the body portion. The guard or back plate C normally lies between the body portion of the front plate B and the arms B², and is formed at its ends with lugs or 85 teats C', which pass through the blade notches A' and into apertures or sockets B³ formed in the front plate and thus fix the position of the blade A with respect to the blade holding means. As shown, the guard 90 C is formed with comb teeth C² and C³ at its opposite edges. The teeth C² project a less distance from the adjacent edge of the blade than do the teeth C³, and in consequence it is possible to get a closer shave 95 by using the edge of the blade guarded by the teeth C² than by using the opposite edge of the blade.

A threaded stud C⁴ projects centrally from the upper side of the back plate C, 100 and when the parts are assembled, passes between the adjacent end surfaces of the arm portion B² of the front plate. The parts are secured together and the blade securely clamped in place between the back plate C 105 and the body portion of the front plate B by means of a nut F screwed onto the stud C⁴ and pressing (indirectly) the free ends of the arms B² toward the adjacent face of the back plate. The nut F, as hereinafter ex- 110

plained, forms a part of my improved handle connection. The resilient arms B^2 are offset as indicated at B^4 . In consequence when the free ends of the arms B^2 are 5 forced toward the front plate by the clamping nut, each arm forms, in effect, a lever of the second class, having its fulcrum at the point where it is connected to the body of the front plate and applying power to the 10 back plate at the foot of the offset portion B^4 .

The handle D comprises a body portion which may be of any suitable form, and bifurcations D' at one end of the body portion by means of which the handle is adjustably secured to the blade holder. As shown, the bifurcations D' are curved, and are shaped to provide surface portions D^2 fitting against a spherical seat E' formed 20 in the upper end of an annular follower or washer member E, which, in the assembled condition of the razor, surrounds the nut F and stud C^4 and directly engages the free ends of the resilient arms B^2 . The 25 bifurcations D' of the handle have adjacent parallel beveled edges D^3 engaged, in the assembled condition of the razor, by the conical portion F' of the clamping nut F. Above its conical portions F' the nut F is formed 30 with a globular portion. In practice, the globular portion of the nut F and the surfaces of the bifurcations D' overlapping it are made approximately spherical with their centers of curvature approximately coincident with that of the spherical seat E' . In 35 the assembled condition of the razor, the bifurcations D' may be slightly spread apart by the wedge action of the conical portion F' of the nut F, and the bifurcations thus 40 gripped between the seat E' and the conical portion F' , so that the globular portion of the nut F is not necessarily in gripping contact with the bifurcations D' . Substantial 45 conformity in shape of the surface of the globular portion of the nut F to the overlapping surfaces of the bifurcations D' is of advantage, however, in maintaining a guided relation of the parts in effecting 50 adjustments.

50 Loosely mounted on the washer E is a sleeve G. A pin E^2 passing radially through, and secured in the wall of the washer E, has its inner end working in a longitudinal slot F^2 in the nut F, and its outer end 55 working in a longitudinal slot G' in the sleeve G. The pin E^2 thus prevents relative rotative movements of the nut F, washer E, and sleeve G, while permitting a limited longitudinal movement of each of those parts 60 relative to the others. The pin E^2 also normally prevents the separation of the parts E, F and G, and thus minimizes the possibility of accidental loss of parts of the razor when the latter is disassembled. A spring 65 H, mounted in a radial opening E^3 in the

washer E has its opposite ends bearing against the adjacent walls of the nut F and sleeve G. This spring creates a slight frictional resistance to the longitudinal movement of any one of the parts E, F and G 70 relative to either of the others. The sleeve G is shown as provided with a knurled rib or collar G^2 to facilitate the relation of the sleeve G and thereby the nut F in clamping together the parts of the blade holder and 75 releasing them. The sleeve G is formed at its end adjacent the blade holder with lugs G^3 , which may be moved into engagement with the blade holder to thereby lock the sleeve G and the nut F against rotation relative to the screw stud C^4 . As shown, the lugs G^3 are adapted to enter the space between the adjacent ends of the two arms B^2 or into notches B^5 in the arms B^2 when the sleeve G is rotated 90° in either direction 80 from either of the two positions in which the lugs G^3 may extend between the ends of the arms B^2 .

In putting a razor blade in place, the nut F is unscrewed sufficiently to permit the 90 guard plate C and blade A to be put in place with the lugs C' passing through the notches A' in the ends of the blade A and into the sockets B³ in the ends of the front plate B. After this, the nut F is tightened 95 sufficiently to clamp the blade holder and inserted blade in place. Then the sleeve G, which has previously been elevated with reference to the washer E and nut F, is moved down to cause the lugs G^3 to enter 100 the spaces between the ends of the arms B^2 , or the apertures or sockets B⁵. The handle D is then adjusted into the position or positions preferred by the user. The adjustment of the handle D thus provided for is 105 practically universal, for the handle may be rotated about the axis of the stud C^4 through a complete circle, and may be turned about an axis transverse to the stud C^4 to vary the inclination of the handle to 110 the axis of the stud C^4 through an angle of about 90° . The tension of the lever arm B^2 , in the operative condition of the razor, insures a sufficient frictional grip of the bifurcations D' of the handle between the 115 conical portion F' of the nut F and the spherical seat E' to prevent accidental displacement of the handle under the forces to which the razor is subjected in normal operation. At the same time the flexibility of the lever arms B^2 is such that the handle may be readily adjusted without applying any force thereto beyond that which can be easily applied by the hands of the ordinary user. 120

The locking of the nut F against rotation through the engagement of the lugs G^3 with the arms B^2 prevents any disturbance of the nut F by the frictional drag of the handle as the latter is adjusted. 125

To remove a razor blade, the sleeve G is retracted, and the nut F backed off to sufficiently loosen the blade holder.

To facilitate cleaning the blade holder 5 the nut F may be screwed off the stud C⁴ so that the arms B² may be moved entirely away from their normal positions, and, of course, the blade holder may be thus opened up to facilitate the insertion and removal

10 of a blade.

The modified form of handle connection illustrated in Figs. 6 and 7 differs from that previously described only in the form of the nut and the manner of interlocking 15 the nut against rotation relative to the surrounding washer E and sleeve G. In these figures the nut FA is formed at its lower end with diametrically opposed, radially extending projections F¹⁰, which pass through 20 notches E³ and G⁴ formed in the ends of the washer E and sleeve G, respectively. The general operation of this form of my invention is essentially the same as that of the embodiment first described. The nut F of

25 Figs. 1-5 may be, and is shown as being made in a single piece, while the nut FA of Figs. 6 and 7 is shown as made of two parts to permit of its injection in the washer. As shown, the globular head F³ of the nut FA

30 is riveted to the body portion F⁴ of the nut.

My improved handle connection may readily be adapted to use with other forms of blade holders than those shown in Figs. 1 to 7, and in Figs. 8 and 9. I have illus-

35 trated the application of my improved handle-adjusting means to an existing form of blade holder of well known type. The blade holder shown in Figs. 8 and 9 comprises a front plate B¹⁵, having its rear face curved and provided with a central threaded stud B¹¹ and unthreaded studs B¹² adjacent each end, which pass through correspondingly located apertures in a flexible double-edged blade A¹⁰. The blade is held

40 in place in this type of blade holder by a back or guard plate C¹⁵, formed with comb teeth at each edge and with apertures receiving the studs B¹¹ and B¹², and the tension of the flexible blade A¹⁰, in any normal

45 adjustment, insures a sufficient frictional grip on the bifurcations D' to maintain the handle D in the desired position or positions during the shaving operation. To lock the nut F or FA, as the case may be, against

50 rotation with the handle in adjusting the latter, the guard plate C¹⁵ is formed with apertures C¹⁶, different pairs of which are entered by the lugs G³ in different angular settings of the latter. Certain features of

55 novelty disclosed, but not claimed herein, are claimed in my copending application, Serial No. 129,915 filed November 7, 1916.

In accordance with the provision of the 60 statutes I have illustrated and described the best forms of my invention now known to

me. It will be apparent to those skilled in the art, however, that changes may be made in the form of the apparatus disclosed without departing from the spirit of the invention hereinafter claimed, and that certain 70 features of the invention claimed herein may sometimes be used to advantage without a corresponding use of other claimed features.

Having now described my invention, what 75 I claim as new and desire to secure by Letters Patent, is:

1. In a safety razor, the combination of a body portion comprising relatively movable parts, a handle formed with a slotted portion curved about an axis perpendicular to the length of the handle, screw threaded clamping means passing through the slot in said handle portion and clamping said portion and the relatively movable parts of the 80 body portion together, and means for releasably holding said clamping means against unscrewing.

2. In a safety razor, the combination of a body portion comprising relatively movable 90 parts, a handle formed with a slotted concavo-convex portion, screw threaded clamping means passing through the slot in said concavo-convex portion and clamping said portion and the relatively movable parts of 95 the body portion together, and means for releasably holding said clamping means against unscrewing.

3. In a safety razor, the combination of a guard plate, a front plate having uprising 100 end portions, arms pivoted to said end portions, and each adapted to engage said guard plate between the ends of the arm, when the latter is in one position and each adapted to be swung away from said position to facilitate cleaning the razor, and clamping means acting between the guard plate and the free ends of said arms and adapted to clamp in place a blade which may be inserted between the front and back 110 plates.

4. In a safety razor, the combination of a guard plate provided with a threaded stud, a front plate, resilient arms hinge connected to the ends of the front plate and adapted 115 to turn into position in which each extends toward said stud and engages said guard plate between the ends of the arm, and to be swung away from said guard plate to facilitate cleaning the razor, and a clamping nut 120 on said stud for forcing said arms against the guard plate to thereby clamp in place a blade which may be inserted between the front and guard plates.

5. A razor handle formed with a slotted 125 concavo-convex portion, and means for adjustably attaching it to a razor body provided with a threaded clamping stud, said means comprising a nut formed with a globular head and a washer formed with an 130

- annular seat for said concavo-convex portion, and means for releasably locking said nut against rotation relative to the stud on which it is screwed.
6. A razor handle formed with a slotted concavo-convex portion curved about an axis transverse to the length of said handle, and means for adjustably attaching said handle to a razor body provided with a threaded 10 clamping stud, said means comprising a washer formed with a seat for the convex side of said curved portion, and a clamping nut formed with a portion extending through said slot and to which said washer is loosely connected and an enlarged portion for engaging said curved handle portion and clamping it against said washer seat, and means for releasably locking said nut against rotation relative to said clamping stud.
7. A razor handle formed with a slotted portion curved about an axis transverse to the length of the handle and means for adjustably attaching said handle to a razor 20 body provided with a threaded clamping stud, said means comprising a washer formed with an annular seat for the convex side of said curved portion, a clamping nut for forcing said curved handle portion against said seat and means carried by said nut and movable into and out of a position in which it may engage a razor body to which the handle is applied to thereby prevent rotation of the nut relative to the 30 clamping stud of said body.
8. An adjustable handle connection for a safety razor blade holder, formed with a threaded stud, comprising in combination a nut adapted to screw on said stud, a washer surrounding said nut and movable 40
- axially with respect thereto, a handle adjustably inserted between said nut and washer, and means movably connected to said nut and adapted to engage a blade holder to which said handle connection may be applied to thereby lock the nut against rotation relative to the stud of said holder. 45
9. An adjustable handle connection for a safety razor blade holder formed with a threaded stud, comprising in combination a 50 nut adapted to screw on said stud, a washer surrounding said nut and movable axially with respect thereto, a handle adjustably inserted between said nut and washer, a sleeve surrounding said washer and axially movable with respect to said nut, means preventing rotative movement of said sleeve and nut, said sleeve being adapted to engage a razor holder to which said handle connection may be applied and thereby lock said 55 nut against rotation relative to the stud of said holder. 60
10. An adjustable handle connection for a safety razor blade holder formed with a threaded stud, comprising in combination a 65 nut adapted to screw on said stud, a washer surrounding said nut and movable axially with respect thereto, a handle adjustably inserted between said nut and washer, a sleeve surrounding said washer and axially movable with respect to said nut, means preventing rotative movement of said sleeve and nut, said sleeve being adapted to engage a razor holder to which said handle connection may be applied and thereby lock said 70 nut against rotation relative to the stud of said holder, and yielding means opposing axial movement of said sleeve and nut. 75

HARRY B. HARTMAN.
